UNITED STATES PATENT OFFICE.

HENRY E. MILLER, OF LINDEN HEIGHTS, OHIO.

SEGMENTAL BLOCK.

1,107,689.

Specification of Letters Patent. Patented Aug. 18, 1914.

Application filed April 4, 1914. Serial No. 829,567.

To all whom it may concern:

Be it known that I, HENRY E. MILLER, a citizen of the United States, residing at Linden Heights, in the county of Franklin and State of Ohio, have invented certain new and useful Improvements in Segmental Blocks, of which the following is a specification.

My invention relates to segmental blocks used for forming circular structures and particularly adapted for building various sizes of sewer conduits. My blocks are so constructed that they may be assembled in interlocking relation to form a smooth continuous inside and outside surface, the main object being the provision of longitudinally extending tongues extending radially inwardly and outwardly along opposite edges of the block. In this manner, one block is always the counter part of another for the same size structure and in this manner the necessity of manufacturing both right and left hand pieces is obviated.

An object of my invention resides in so constructing my blocks, that it is not absolutely necessary to use a form when building a conduit. To overcome this, I have resorted to a structure which temporarily locks one block to another when they are in assembled relation, so that they may not accidentally disengage themselves.

Other objects of my invention will become more apparent after a detailed description of the accompanying drawings, in which similar characters of reference designate corresponding parts, and in which:

Figure 1 is an end view of the upper portion of a conduit section, in which my blocks are used, Fig. 2 is a plan view of the upper half of a conduit section showing the manner in which the blocks may be assembled in building the same, Fig. 3 is a view in perspective of one of the blocks shown separate, and, Fig. 4 is a side elevation of the structure shown in Fig. 3.

I will first describe the preferred construction of one of the blocks themselves and then describe the manner in which they are assembled. Referring particularly to Figs. 1 and 3, it will be noted that each block comprises a main body formed of curved outer and inner walls 1 and 2, these walls being held spaced from each other by means of radially outwardly extending walls 3 and 4. These walls coöperate to form a longitudinally extending hollow portion 5, which is

desirable to give lightness of weight and to facilitate the heating of the block when made of clay or a like substance. Extending longitudinally along the walls 3 and 4 are radially projecting tongues 6 and 7, both of these tongues being spaced somewhat from the walls of the main body portion to form grooves 8 and 9. In order to avoid making right and left hand blocks, I have so arranged these tongues that the member 6 projects radially inward from the overhanging portion 10 of the upper wall 1, while the member 7 projects radially outward from an overhanging portion 11 of the lower wall 2. Both the tongues 6 and 7 and likewise the grooves 8 and 9 are of equal height and depth so that all blocks made from the same mold will be symmetrical with respect to each other and will further interlock in the manner desired. Each block is also provided with a supplemental tongue and groove structure designed to assist in building up a conduit section so that the various blocks, during the process of construction, will not collapse and will further be held in their correct position without the use of a form. At 12 I have shown a laterally projecting longitudinally extending tongue along the outside face of the radially outwardly extending tongue 7. This supplemental tongue 12 is designed to coöperate with a groove 13 formed in the sides of the wall 3 of the main body portion to lie adjacent the inwardly projecting tongue 6 of the adjacent block. The ends of each block are also preferably formed with cut-out portions 14 to form end grooves and projecting portions 14^a to form end tongues. Referring to Fig. 1, it will be noted that all of the blocks being of identical structure, they may be assembled to form a conduit in the manner shown, all the tongues and grooves 6, 7 and 8 and 9 coöperating to form an interlocking structure. It is, of course, understood that mortar or other sealing structure is to be used in the correct amounts. Referring to Fig. 2, wherein is shown a plan of the upper half of a conduit, it will be noted that these blocks are assembled in step by step order, this order being such that the succeeding top block is always in the rear of the lower ones to the extent of half the length of a block. This is the desirable way of building up a section and is further rendered necessary by the peculiar supplemental tongue and groove structure.

For instance, the three blocks to the right of Fig. 2, numbered 15, are in position, as well as those blocks numbered 16 and 17. It is then desired to place the next one 18 in position and this may be done without sliding the section endwise into position. The supplemental tongue 12 is made small enough so that the section 18 may be slid into the position shown in Fig. 1, by bringing the adjacent walls 19 and 20 of the radially projecting tongues 7 and 6 respectively into contacting engagement with each other. In other words, the amount the tongue 12 projects out from the face of the radially projecting tongue 7 is approximately equal to the space left between the various sections and adapted to be later filled with mortar. After the block has thus been placed in position, by its own weight, it moves so that the supplemental tongue 12 and the groove 13 will come in engagement. Because of this engagement, the block 18 will be supported at points 21 and 22 and it is, therefore, impossible for this block to become accidentally dislodged. When I state that the blocks are supported at this point, I take into consideration also that a sufficient amount of mortar has been placed at these points to guard against all possible leakage in or out of the conduit section. After the block 18 has thus been placed in position, the succeeding blocks 23 and 24 may be likewise assembled.

From the above description, taken in connection with the accompanying drawings, it will be apparent that the structure I have provided, permits the building up of a conduit section without the use of a form, this latter feature being accomplished principally by the provision of the supplemental tongue and groove structure 12-13. In addition, the structure is such that all parts are

formed identically and rights and lefts done away with. Also, the abutting portions of all blocks are formed of an interlocking nature, 45 so that leakage in or out of the conduit section is positively precluded.

While I have shown my invention as applied to segmental blocks, I wish it to be understood that the same may also be applied to blocks of other shapes and further, it is immaterial whether the supplemental tongues and grooves 12 and 13 be interchanged from that shown in the drawings or whether they be on opposite faces of the 55 main tongues and grooves. It is essential, however, that some portion of the main tongues and grooves carry these supplemental tongues and grooves and it is to be understood that the appended claim is to be 60 interpreted in the light of this paragraph.

What I claim, is:

A segmental block comprising a body portion, longitudinally extending tongues along opposite edges of said body, said tongues being both spaced from said body to form a groove between each tongue and said body, one of said tongues projecting radially inward from the outside portion of the block and the other projecting radially outward from the inside portion of the block, the side of said body portion adjacent the inwardly projecting tongues being provided with a longitudinally extending groove, and a laterally projecting longitudinally extending tongue along the outside face of said 70 radially outwardly extending tongue.

In testimony whereof I affix my signature in presence of two witnesses.

HENRY E. MILLER.
